UNITED STATES PATENT OFFICE.

CHRISTIAN G. CHRISTIANSEN, OF FINGAL, NORTH DAKOTA.

HORSE NOSE GUARD.

Application filed December 9, 1926. Serial No. 153,659.

This invention relates to certain improvements in horse nose guards; and the nature and objects of the invention will be readily recognized and understood by those skilled in the art in the light of the following explanation and detail description of the accompanying drawings illustrating what I, at present, consider to be the preferred embodiments or mechanical expressions of my invention from among various other forms, arrangements, combinations and constructions, of which the invention is capable within the spirit and the scope thereof.

The invention is primarily directed to those types of nose guards for horses employed as a protection for and against certain species of flies and other insects which attack and bite or sting a horse's mouth and nose, and which are met with in certain sections of the United States. A particular type of such nose guard is formed of leather or other suitable flexible materials, but with such types experience in use has developed certain disadvantages and inefficiencies therein, among which may be mentioned, particularly, the tendency or possibility of the nose guard being displaced from proper position by movements of the horse to thus expose the horse's nose to attack, and also the incomplete protection afforded portions of the horse's nose subjected to attack.

It is an object of this invention, therefore, to provide a horse nose guard of the leather or flexible material type in which the foregoing difficulties and disadvantages, as well as certain others, are overcome and practically eliminated so as to secure a maximum of protection for the horse's nose, while retaining the desired characteristics of simplicity of construction with low cost of manufacture, and durability in use.

A further object of the invention is to provide a nose guard of the general type referred to, which is so designed and constructed as to eliminate possibility of displacement from position on the horse's nose by movements of the horse or shaking of its head, all without binding or causing discomfort to the horse, or hampering or obstructing the horse's nostrils and free natural breathing.

A further object of the invention resides in the provision of a horse nose guard of the type designed for protecting the horse's nose

and mouth from the attacks of flies or insects, which is so designed and arranged as to permit of its being mounted in position on a horse's nose and attached to bridles of various types and designs, thus giving the guard a wide range of usefulness, without calling for or requiring a special type or design of 55 bridle, or other special means for attaching the guard in position. With the foregoing and certain other objects and results in view, which other objects will be readily apparent to those familiar with this art from the following explanation, the invention consists in certain novel features in construction and in combinations and arrangements of parts as will be more fully referred to and specified 60 65 70 75 80 85 90 95 100 105

Referring to the accompanying drawings, Fig. 1 is a view in side elevation of a horse's head with a nose guard of the invention mounted in position over and protecting the mouth and nose of the horse, and attached 70 to a bridle on the horse's head.

Fig. 2 is a view in side elevation of the nose guard of Fig. 1 removed from mounted position on the horse's head.

A form of the invention is disclosed in the accompanying drawings purely by way of example and not of limitation for the purpose of explaining and presenting the various features of the invention. In this form of the invention, a nose guard embodies and includes a leather, or other suitable flexible material, mouth receiving and protecting member 1, which in the present instance decreases in width toward its opposite ends where it terminates in the decreased relatively narrow width strap forming ends 8. At the central portion of the lower side of the member 1, spaced slits or cuts are formed therein and the member is then folded into U-shape with the opposite reduced width end portions thereof spaced apart to form the sides of the member, and the central lower portion between the slits or cuts is drawn in together or riveted or otherwise secured to form the tucked or upwardly extending portion 1' of the member. This member so formed, is designed and arranged to fit over and receive the horse's mouth as will be clear from Fig. 1 of the drawings.

A nose encircling strap or band 3 of anular form is provided with the strap ends

8 of member 1 secured thereto at opposite sides thereof, so that this nose encircling strap is disposed extending upwardly above and downwardly below the strap ends 8 and 5 the member 1. Any suitable or desired fastening or attaching means such as the ring 7 are provided at the outer ends of the strap portions 8 by which the nose guard can be readily attached to a bridle or other head 10 gear on the horse, as will be explained hereinafter.

A curved or arcuate flexible material jaw receiving and protecting member 5, is provided extending across and between and secured to opposite lower sides of member 1, spaced rearwardly and upwardly from the tucked portion 1' of the lower end of the member 1. A strap 4 extends rearwardly between and is connected to jaw receiving 15 member 5 and the lower section of nose encircling strap 3, centrally of these members and forming a rearward continuation of jaw receiving member 5 to increase the area thereof, as well as to maintain the lower 20 section of strap 3 properly positioned from and with respect to member 5 and the mouth receiving member 1. A nose protecting and covering member 2 is secured, extending between the upper forward central portion of nose member 1, and the central portion of the upper section of nose encircling strap 3, so that this member 2 forms a continuation 25 of mouth receiving member 1, while at the same time, maintaining and properly positioning the upper section of strap 3, spaced 30 from the mouth receiving member 1.

Preferably, although not necessarily, the above described members forming the nose guard are made of leather and suitably riveted 40 or sewed together to provide the necessary strength and durability for the device. If desired, strings or thongs 6 can be provided attached at spaced intervals to the upper section of strap 3 at opposite sides of the nose member 2 so as to extend or depend loosely 45 across and over the breathing or nostril space 6' between member 2 and the nose member 1, as clearly shown in Fig. 1 of the accompanying drawings.

50 A nose guard of the invention, constructed and designed as above described, is mounted and attached in position on and protecting a horse's nose and mouth as indicated in Fig. 1, with the horse's mouth received in the member 1 which extends over and along opposite sides of the horse's nose. The strap or band 3 fits over, around and completely encircles the horse's nose, with the nose piece or member 3 extending over and along and 55 protecting the upper side of the nose, while the member 5 fits around and receives the lower or under jaw of the horse to cover and protect the same, which protection is increased by the jaw strap 4 extending rearwardly to strap 3. The nose guard is se-

cured and maintained in this position over and protecting the nose and mouth of the horse by attaching the rings 7 at opposite sides of the horse's head to the bridle 70 b (see Fig. 1) or other head gear of the horse. In this manner and by this construction and arrangement, the nose guard is adapted to attachment of various types and designs of head gears which is an important feature in view of the fact that no standardized type of 75 bridle is employed. It will here be noted, referring now to Fig. 1, that the horse's nostrils are disposed and lie within the spaces 6', between mouth piece 1 and nose piece or member 2 to permit of free, natural 80 breathing of the horse, while the strings or thongs 6 depending across these openings will prevent flies from entering the same and attacking the horse.

By the provision and arrangement of the 85 nose encircling band or strap 3, forming in effect an endless strap, not only are the various members forming the nose guard attached thereto and maintained in the proper spaced relation thereby, but all possibility 90 of the nose guard being displaced upwardly, as for example by shaking of the horse's head is eliminated, which feature and function is assisted materially by the lower jaw strap 4, as will be readily understood. This 95 is an important feature of applicant's invention as such type of nose guard is of no practical utility if it can be displaced by the horse, for the minute it becomes displaced, the lower jaw and mouth are exposed to the attacks of the flies or insects and the purposes for which such device 100 are employed are thereby defeated.

A device of the invention is of extremely simple and inexpensive construction enabling it to be readily formed from leather or other suitable flexible material to result in a device which will withstand the strains and abuses to which it is placed in use and last for a considerable length of time.

110 It is also evident that various other forms, arrangements, combinations and constructions might be resorted to without departing from the spirit and the scope of my invention, and hence I do not wish to limit myself to the exact and specific disclosures hereof.

Desiring to protect my invention in the broadest manner legally possible, what I claim is:

1. In a horse nose guard, a mouth receiving and protecting member, a nose encircling strap, said mouth member secured at its opposite spaced side ends to opposite sides of said encircling strap, a nose covering member extending from the upper side of said mouth member to the upper side of said encircling strap, a lower jaw receiving member extending across and between the spaced lower sides of said mouth member, and a jaw protecting member extending rear- 120 125 130

wardly from said jaw receiving member to the lower side of said encircling strap.

2. In a horse nose guard, in combination, a mouth receiving and protecting member terminating in spaced opposite side ends, a nose encircling strap, the spaced ends of said mouth member secured to said encircling strap at opposite sides thereof, a lower jaw

receiving member extending across the under side of said mouth member between the spaced sides thereof, and a member extending from the intermediate portion of said jaw member rearwardly to and connected with the lower portion of said encircling strap.

CHRISTIAN G. CHRISTIANSEN.
